SURGE ARRESTER

Filed March 7, 1923

Inventor:
Irving S. Crocker,
by Alexander S. Hunt.
His Attorney.

UNITED STATES PATENT OFFICE.

IRVING S. CROCKER, OF LYNN, MASSACHUSETTS, ASSIGNOR TO GENERAL ELECTRIC COMPANY, A CORPORATION OF NEW YORK.

SURGE ARRESTER.

Application filed March 7, 1923. Serial No. 623,532.

My invention relates to surge arresters and is particularly adapted for the protection of incandescent lamps on series lighting circuits.

With the advent of incandescent lamps having filaments of materials having a positive temperature coefficient, such for example as tungsten or tantalum, and their use in such circuits in lieu of carbon filament lamps, a serious difficulty has arisen because of the burning out of lamps due to surges on the line. The older form of carbon filament lamps was not so sensitive to sudden increases in current inasmuch as the carbon of their filaments had a nearly zero or a negative temperature coefficient. A lamp with a filament having a positive temperature coefficient such as tungsten or tantalum is, however, extremely sensitive to variations in current, hence abnormal increases in current due to surges in the line have frequently resulted in burned out lamps. Not only are the incandescent lamps frequently damaged by such surges, but other devices and the line itself are frequently injured. Where, for example, a rectifier tube is arranged to supply a constant current circuit, if the rectifier tube goes bad there is usually a period of time during which the circuit is flashing continually and any arc lamps which may be on the circuit are subjected to a terrific pounding which many times results in their destruction. Such surges are particularly apt to damage the line where cables are used since the insulation of the cables is broken down.

An object of my invention is to provide a simple and reliable arrangement which will prevent damage to incandescent lamps on circuits of the class described, prevent damage to the line, prevent damage to other apparatus connected to the line from line surges of the character described, and also prevent injury to the line and the apparatus connected thereto from abnormal voltages even though the current in the line is normal.

My invention will be better understood by reference to the accompanying specification and drawing and its scope will be pointed out in the appended claims.

The single figure of the drawing is a diagrammatic representation of my invention, showing the apparatus and the connections thereof to the distribution circuit.

Referring to the drawing, 1 and 2 are the two sides of a load circuit which for example may be fed from a series mercury arc rec-

tifier or from a constant current transformer of the type shown for example in the patent to Elihu Thomson, No. 516,846, and in this circuit are shown series connected arc lamps 3 and incandescent lamps 4. A short circuiting plug switch 5 and secondary plug switches 6 and 7 may be used to control the lighting circuit. A horn gap arrester comprising a pair of horns 8 carried by a pair of rods 9 is connected across the line in parallel with the lamps by conductors 10 and 11. The rods 9 also carry a pair of spark gap terminals 12 and 13, one of which, namely, terminal 13, is shown insulated by a bushing 14 from the rod by which it is supported. These terminals are also connected across the line in parallel with the lamps 3 and 4 as shown. A lever 15, having one end pivotally mounted at 16, carries at its free end a pair of upstanding ears 17 and pivoted to these ears is a wedge shaped member 18 adapted when the lever is in its raised position to make contact with both horns 8 of the horn gap arrester. The lever normally gravitates to its lowered or inoperative position and for actuating the lever to raise it to a position short circuiting the horn gap, an electromagnet including a plunger 19 and solenoid 20 is provided, the solenoid being connected in series with the conductor 2 at a point between the points of connection thereto of the horn gap arrester and the spark gap.

The operation of the device will be readily apparent. When the current in the rectified or transformed circuit increases to an excessive amount due to a surge in the main line, the lever 15 is actuated by the plunger 19 and solenoid 20 to bring the member 18 into short circuiting position across the horn gap arrester. The lamps 4 are thus shunted and are effectively protected from the excessive current. As soon as the short circuit is established, however, the solenoid, being also shunted, becomes deenergized and allows the lever to drop to its normal position. Supposing for example that the coils of the rectifier transformer or the constant current transformer are separated a distance corresponding to the normal full load current, the increased repulsion between the two coils when the surge occurs forces the floating coil away, but the arc will hold at the horn gap until the coil has reached its short circuit position. The arc then breaks and the floating coil thereupon resumes its normal load.

position, the arc and incandescent lamps in turn resuming their normal operation. Thus the entire operation takes place automatically, the lamps are fully protected from the 5 effects of the surge and after the surge has passed the apparatus is ready to take care of another surge without requiring any manipulation by an operator.

The spark gap between terminals 12 and 10 13 functions to pass a high voltage which may be produced on the line while the current is yet normal. Such voltage upon jumping the spark gap will pass through the solenoid and back to the rectifier or constant current machine. The resulting abnormally 15 high current, produced by reason of the relative position of the coils at that time, will effect the operation of the short circuiting lever, the short circuit being subsequently removed and the arc thus drawn extinguished 20 in the same manner as before.

It will thus be seen that I have provided a device which will automatically protect 25 from the evil effects of surges lighting circuits of the character described employing incandescent lamps whose filaments are particularly susceptible to such surges and while I have described only one embodiment of my invention, I do not wish to be limited to

the particular form shown and described as it 30 will be apparent that many modifications therein may be made without departing from the scope of my invention as set forth in the appended claims.

What I claim as new and desire to secure 35 by Letters Patent of the United States, is:

1. In combination in an electric system, a line adapted to be connected to a source of current, an electric device connected across said line and operated by current supplied 40 over said line, an electromagnet in series with said line, a spark gap across said line, and means under the control of said electromagnet for mechanically short circuiting said spark gap and said line. 45

2. In combination in an electric system, a line adapted to be connected to a source of current, an electric device connected across said line and operated by current supplied over said line, an electromagnet in series with 50 said line, a spark gap across said line, means under the control of said electromagnet for mechanically short circuiting said spark gap, and a second spark gap across said line, said 55 spark gaps being of different character.

In witness whereof, I have hereunto set my hand this 2nd day of March, 1923.

IRVING S. CROCKER.
